[57] CLAIM

The ornamental design of apparatus for developing
X-ray films, substantially as shown.

DESCRIPTION

FIG. 1 is a plan view of an apparatus for processing
X-ray films, according to the invention;

FIG. 2 is a front elevation view of the apparatus in FIG.
1;

FIG. 3 is a right side elevation view of the apparatus in
FIG. 2;

FIG. 4 is a left side elevation view of the apparatus in
FIG. 3;

FIG. 5 is a side perspective view of the apparatus in
FIG. 1;

FIG. 6 is a backside elevation view of the apparatus in
FIG. 1; and

FIG. 7 is a bottomside view of the apparatus in FIG. 1.

FIG. 1

FIG. 2

FIG. 3

FIG. 4

FIG. 5
